US0D1099884S

(12) **United States Design Patent** (10) Patent No.: **US D1,099,884 S**
(45) Date of Patent: ** Oct. 28, 2025

(54) **ARRAY BOX**

(71) Applicant: **Battelle Memorial Institute**,
Columbus, OH (US)

(72) Inventors: **Andrew M. Sweeney**, Columbus, OH
(US); **David R. Chase**, Gahanna, OH
(US); **John Bartholomew**, Hilliard, OH
(US); **Curtis A. Hudberg**, Westerville,
OH (US); **Alexandra L. Paulsel**,
Denver, CO (US); **Michael Jansen**, San
Luis Obispo, CA (US)

(73) Assignee: **BATTELLE MEMORIAL
INSTITUTE**, Columbus, OH (US)

(**) Term: **15 Years**

(21) Appl. No.: **29/917,182**

(22) Filed: **Nov. 17, 2023**

(51) LOC (15) Cl. **14-02**

(52) U.S. Cl.

USPC **D14/242**

(58) **Field of Classification Search**

(57) **CLAIM**

The ornamental design for a array box as shown and described.

DESCRIPTION

FIG. 1 is a front top perspective view of the array box;
FIG. 2 is a top view of the array box;
FIG. 3 is a bottom view of the array box;
FIG. 4 is a left side view of the array box;
FIG. 5 is a right side view of the array box;
FIG. 6 is a front view of the array box;
FIG. 7 is a rear view of the array box; and,
FIG. 8 is a rear left perspective view of the array box.
The broken lines immediately adjacent to the claimed area
depict boundaries of the claimed design or environmental
structure, and form no part of the claimed design.

1 Claim, 8 Drawing Sheets
